UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING.

1,357,807.

Specification of Letters Patent.

Patented Nov. 2, 1920.

Application filed September 5, 1919. Serial No. 321,753.

To all whom it may concern:

Be it known that I, JOHN F. O'CONNOR, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part 10 of this specification.

This invention relates to improvements in side bearings.

One object of the invention is to provide a simple and efficient, relatively inexpensive, 15 side bearing for railway cars and which is particularly adapted for attachment to the under side of a body bolster.

In the drawing forming a part of this specification, Figure 1 is a vertical sectional view of portions of a body and a truck bolster of a car showing my improvements in connection therewith. And Fig. 2 is a vertical sectional view taken substantially on the line 2--2 of Fig. 1.

25 In said drawing, 10 denotes the upper section of a truck bolster of a railway car and 11 the lower section of an opposed body bolster. As shown, my improved bearing is attached to the under side of a body bolster 30 and the anti-friction element is normally spaced a slight distance from the truck bolster.

The improved bearing, as shown, comprises, broadly, a housing or retaining member A, an anti-friction element proper B, and a pair of combined centering and supporting springs C—C.

The housing or retaining member A will ordinarily be made in the form of a malleable casting and has an upper wall 110, spaced depending side walls 111—111, and curved end walls 12—12. Said member A is provided at the corners thereof with suitably perforated lugs 13—13 by which it is 45 riveted or otherwise rigidly secured to the body bolster.

The anti-friction element B, as shown, is of generally triangular formation and has three arcuate surfaces 14, 14^A and 14^B struck 50 on relatively long radii and three arcuate surfaces 15, 15^A and 15^B struck on relatively short radii. The surfaces 14 and 15; 14^A and 15^A; and 14^B and 15^B are made concentric so as to obtain a proper rolling action. Said

element B is preferably made in the form of 55 a casting suitably hardened and, at the top thereof, it is provided with extensions or lugs D—D. These lugs D are provided on their under surfaces with rounded edges indicated at 16 and said lugs are projected upwardly beyond the corresponding arcuate bearing surface 14, as indicated at 17 in Fig. 1. The extensions 17 are received in tapered openings or guideways 18 formed in the retaining member A so that the lugs D are 60 utilized as centering and guiding means for the anti-friction element B. The inner faces of the side walls 111 of the retaining member A are provided with ribs 19—19 arranged to act as a continuation of the guiding or centering recesses 18.

To support the anti-friction element B, the springs C are utilized, one on each end of the element. Each spring C is preferably formed from spring wire and is of a general 75 oval form having at the top thereof a depression 20 to form a suitable yieldable bearing for the corresponding lug D. At the bottom, each spring C has the ends thereof indicated at 21 turned downwardly so as to 80 fit in a recess 22 provided in the retaining member A. The recesses 22 are really notches in inturned flanges 23—23 formed along the lower edges of the side walls 111 of the retaining member A. The springs C 85 are inserted through suitable perforations 24 in the end walls 12 of the retaining member A.

The normal position of the parts is as shown by the full lines in Fig. 1 in which 90 condition it is evident that the anti-friction element B is supported clear of the truck bolster by the springs C. When the bearing is brought into action and the element B is rolled to either side of normal, as for instance to the position indicated by the dotted lines B' in Fig. 1, it is evident that the lugs D will be swung downwardly and thereby compress the springs C. The limit of movement of the anti-friction element B is 95 obtained when the element B engages against the corresponding end wall 12, the latter being preferably curved to conform to the curvature of the surfaces 14 and 14^A. When the pressure on the bearing is removed, the 100 anti-friction element B will return to normal under the influence of the springs C and also under the influence of gravity since 105

the anti-friction element B will have a tendency to swing about the lugs D as fulcrums on the springs C.

The device is simple, compact, relatively inexpensive to manufacture and apply. The device herein shown and described is the preferred construction, the same is merely illustrative and I contemplate such changes and modifications as come within the scope 10 of the claims appended hereto.

I claim:

1. In an anti-friction bearing, the combination with a housing adapted to be attached to the bolster, of an anti-friction 15 element mounted within said housing and adapted for movement back and forth therein, said element having lugs extended from its ends, means on the housing directly engaging and coöperating with said lugs to center said element, and springs interposed 20 between said housing and said lugs and directly engaging and coöperating with the latter to return said element to central normal position after actuation thereof, said 25 springs supporting the anti-friction element.

2. In an anti-friction bearing, the combination with a housing adapted to be secured to the under side of a body bolster 30 and open at its bottom, of an anti-friction element mounted within said housing and depending partly below the latter, said element being adapted for movement back and forth within the housing and having lugs 35 extended from its ends, means on the housing coöperable with said lugs to center said element, and springs interposed between said housing and said lugs and coöperable with the latter to return said element to 40 central normal position after actuation thereof, said springs supporting the anti-friction element.

3. In an anti-friction bearing, the combination with a housing adapted to be attached to a bolster, of an anti-friction element 45 mounted within said housing and adapted for movement back and forth therein, said element being of substantially triangular form having three sets of concentric bearing surfaces, each set consisting of

a bearing surface struck on a relatively long radius and a bearing surface struck on a relatively short radius, coöperating means on said element and the housing arranged to center said element, and spring means interposed between said element and the housing arranged to return said element to central normal position after actuation thereof, said spring means pivotally supporting 55 said element.

4. In an anti-friction bearing, the combination with a hollow housing adapted to be attached to the under side of a body bolster and open at its bottom, of an anti-friction element mounted within said housing and depending partly therebelow, said element being of substantially triangular formation and having three sets of concentric bearing surfaces, each set consisting of a bearing surface struck on a relatively long radius and a bearing surface struck on a relatively short radius, said element having lugs extended from the ends thereof at the top, means on said housing coöperable with said lugs to maintain said element in central position, and spring means coöperable with said lugs to return said element to normal position after actuation thereof.

5. In an anti-friction bearing, the combination with a hollow housing adapted to be secured to the under side of a body bolster, said housing being open at the bottom and having an upper wall adapted to act as a bearing surface, of an anti-friction element mounted within said housing and depending partly therebelow, said element having lugs extending from the ends thereof at the top, the housing having recesses within which said lugs are disposed to thereby properly center the anti-friction element, and loop-shaped springs at each end of said element supported within the housing, said springs engaging the under sides of said lugs and pivotally supporting the latter.

In witness that I claim the foregoing I have hereunto subscribed my name this 27th day of Aug., 1919.

JOHN F. O'CONNOR.
